[57] CLAIM

The ornamental design for a pulley and belt guard for a portable bag closing sewing machine, as shown and described.

DESCRIPTION

FIG. 1 is a perspective view of a pulley and belt guard for a portable bag closing sewing machine showing our new design;

FIG. 2 is a top plan view thereof;

FIG. 3 is a front elevational view of FIG. 2;

FIG. 4 is a right side elevational view of FIG. 2;

FIG. 5 is a left side elevational view of FIG. 2, and A bottom view is not shown and is conventional in configuration.
